MULTIPLE SOLID ENERGY EMITTER

Chester H. Braselton, New York, N. Y., assignor
to Sirian Lamp Company, Newark, N. J., a cor-
poration of Delaware

Application August 19, 1930, Serial No. 476,342

6 Claims. (Cl. 176—1)

This invention relates to energy radiating apparatus, and particularly to that type of apparatus which utilizes an ionized gaseous atmosphere, in conjunction with an electric conductor.

5 One of the objects of the present invention is to provide an energy radiating device which employs as an element of the radiator, a material which emits energy selectively, when heated. Another object is to provide a radiator combining a selective emitter and a heating unit, which heating unit also functions as a radiator.

Still another object of the invention is to utilize, as far as possible, the total energy output of a radiator of the type employing a metallic conductor in an ionizable gas, which gas is activated by ionization in a region adjacent the conductor. Further objects of the invention relate to novel means for supporting the heating means with reference to the selective radiator, and to other features of the invention which will become apparent on consideration of the following description and of the accompanying drawings, in which:

Fig. 1 is a view in elevation of one form of the radiator, which may be preferred;

Fig. 2 is a detail partly in section of the radiator unit;

Fig. 3 is a modification of the radiator of Fig. 1, showing a different mode of support for the heater;

Fig. 3a is a view in elevation of another embodiment of the radiator;

Fig. 4 is a view of another modification of the invention; and

Fig. 5 illustrates a modified type of selective radiator adapted for use in the apparatus of Fig. 4.

In my related application, Serial No. 459,048, filed June 3, 1930 I have described a type of energy radiating device in which energy is radiated by an activated layer of ionized inert gases in juxtaposition to a conductor coated with a rich ionizing material. With an appropriate pressure of gas and proper voltages, it has been found that a halo forms about the conductor which serves as an auxiliary conducting path for an electric current, and also as an important source of radiation, usable either for lighting purposes or for any other purpose which requires the application of radiated energy of definite wave frequencies.

In accordance with said application, a filament of appropriate resistance, such, for example, as 150 ohms, is coated with various alkaline earth metal oxides such as the oxides of barium, cal-

cium, or other materials preferably of low electron evaporation constants which have been found to emit electrons densely when heated. The base filament is preferably tungsten wire, although other metal conductors may be used. It is not necessary that the base material be highly refractory as the operating temperatures are relatively low, in many cases not being above that of low red heat. The filament is preferably coiled and coated with materials as above mentioned, 5 which may be initially in the proportions of 40 grams of barium carbonate, 40 grams of calcium carbonate, 8 grams of barium nitrate with a binder of sufficient nitrocellulose dissolved in amyl acetate to hold the coating on the wire, 10 and mounted on a stem support sealed in the bulb of the envelope and the whole baked at a temperature of about 400° C. while a current is passed through the filament heating the same to about 600° C. and evacuated to a pressure of 10 about $\frac{1}{2}$ micron in order to remove water vapor and other gases which may be occluded in the envelope. The potential is then slowly elevated 15 to about 800° C., thus gradually heating the coating on the filament until the temperature arrives 20 at a red heat. Gases emitted from the coating and interior of the bulb are in the meantime being removed by the vacuum pump and the pumping is continued until the pressure is approximately .5 micron. The oven is then removed 25 30 and the current raised to heat the filament to about 1200° C. The pump is then shut off and neon gas is again admitted to about $\frac{1}{2}$ mm. of mercury, and a potential applied and raised until a reddish discharge completely fills the bulb, this 35 discharge being concentrated intermediate adjacent parts of the radiator. The filament temperature is then raised to about 1400° C. The bulb is then exhausted to about .5 micron, thus completing the activating process for the coating. 40 To complete the radiator neon gas is admitted to a pressure of 50 mm. of mercury, and then argon gas is also added until the pressure is approximately 200 mm. of mercury. Of course, the values of voltages, resistance and gas pressure 45 mentioned may be varied within limits in accordance with requirements.

Referring now to the drawings, Fig. 1 illustrates a radiator of the general type hereinabove described, and having improved modifications, 50 as will now be set forth. In the envelope 10 is sealed a stem 11, on which is mounted three standards 12, 13, and 14. Adjacent the terminals of standards 12 and 14 is secured a coil 9 of tungsten wire 15 having a coating of electron 55

emitting material 16 approximately throughout its coiled length.

The wire of the coil 9 may be either straight or closely coiled so as to increase the effective resistance per unit length. The coating 16 may be of various alkaline oxides, but a mixture of oxides of barium and calcium may be specified as usable in this particular type of radiator. Within the coil 9 of this coated tungsten conductor is positioned a rod or pencil 17 which, when heated, selectively radiates in certain well defined frequency ranges, such as that of the luminous range. Such materials for illuminating purposes are various oxides of rare earth metals such as cerium, yttrium or oxides of thorium, magnesium and calcium.

The pencil 17 is supported along the axis of the coil 9 by means of the inturned ends of the standards 12 and 14 which penetrate into axial recesses 18 and 19 of the pencil 17, as illustrated in Fig. 2 of the drawings.

The standard 13 is spotwelded or otherwise attached to the approximate mid-point of the coil 15 to serve as an auxiliary support therefor, and prevent sagging with consequent contact of the pencil 17 and the coil 15.

In operation, when the electric potential is applied to the connecting circuits 20 and 21, which in turn are attached respectively to the conducting standards 12 and 14, the filament 15, with its attached coating 16, is heated until electrons are heavily emitted from the coating and an energized atmosphere of ionized gas forms as a halo about the conductor, the diameter of which depends upon the pressure of the inert gases, such as argon and neon, within the bulb. The heat energy derived from the ionized gas by bombardment, as well as by radiation and convection of gases from the filament 15, heats up the pencil 17 to a point where it begins to selectively radiate energy. Where a lamp for illuminating purposes is contemplated, the gases are so chosen and the pencil and heater material is so selected that in the operating temperatures a high density of luminous radiation is provided.

The exact type of radiation may be varied over wide ranges, not only within the luminous range, but above or below said range. For instance, a radiator of ultra-violet energy may be designed as well as a radiator of wave length of lower frequency than that of red light. The total energy effect is the sum of that derived from the heating conductor, the ionized gases surrounding the conductor and the emitting solid body, so that a radiator of maximum efficiency is available.

In Fig. 3 a means of supporting the heating conductor 15 is shown, which varies from that of Fig. 1 in that the approximate midpoint of the conductor is connected by a conductor 30 to a pencil 17, thus forming a ground or shunt connection. The utility of this modification lies chiefly in radiators of the type which employ a high voltage and in which it is desirable to break the potential drop into a series of segments, according to the principles described in my co-pending application Serial No. 476,960.

In Fig. 4 of the drawings a modified form of radiator is illustrated in which the solid emitter 70 is not a part of the electrical circuit, but consists of an insulated solid cylindrical unit 40, adapted to be positioned within the coated heater coil 41. This emitter is mounted on the standard 42 in the stem 43 of the bulb 44, and carries 75 at its upper end a flat enlargement forming the

head 45 which serves as the main energy emitter of the device.

In the case of the prior modification the electrical conductivity of the emitter affects the operation of the device and ordinarily the resistance should be high. In the modification of Fig. 4, however, the electrical characteristics are of minor importance.

In operation, heat as derived from electronic and ionic bombardment, from radiation, and gas 10 convection, is received by the cylindrical member 40 and conducted to the radiating head 45. In addition to the connecting standards 46 and 47 by which the coil 41 is supported, and through which electrical conductance is made to the exterior of 15 the bulb, there is provided an additional supporting standard 48. Other supporting means may also be utilized to the amount necessary to prevent the coil and the heater from sagging and contacting with each other. 20

In Fig. 5 I have illustrated a modification of the solid emitter of Fig. 4, in that the cylindrical body 40 of selective emitting material, such as calcium oxide, is replaced by a refractory metal conductor 50, such as tungsten, this body terminating in a disc-like head 51, which in turn fits into a recess 52 formed in the base of a head 53 of selective emitting material of the type utilized in the solid emitter of Fig. 4; that is, calcium oxide. This construction is advantageous, as the 30 greater rapidity of the heat conduction of tungsten or other refractory metal reduces the time limit in which the radiator becomes effective after the electrical circuit is closed. Instead of placing the coating material externally of the coil, 35 the same may be applied within the coil in the shape of a rod or pencil or as a plastic core material which is subsequently hardened by baking. Accordingly, in the claims hereto appended, the term "coating" is intended to cover both inner 40 and outer applications of the coating material.

The gases employed have been referred to as monatomic and as readily ionizable, or as vapors of metals. Other gases than those mentioned, such as nitrogen, may be employed, providing 45 appropriate controlling factors are introduced. A fundamental requirement appears to be in connection with these gases that the breakdown potential of the same along the axis of the conductor be less than the potential necessary to raise the 50 temperature of the electron emitting material or coating to its operative temperature of electron emission.

The various turns of the coil 9 are illustrated as separated relatively widely, but in practical 55 operation these coils may be more closely spaced together, and this will be the case whether or not the wire of the coils is straight or itself coiled, as shown in Fig. 1. Moreover, it is not necessary that the coating, if applied externally, be about 60 the whole outer surface of the coils, but may lie only on the inner surface of the coil.

Various other modifications of the invention may be described, all of which utilize the general idea of associating with the combined metal and gas conductor unit a solid emitting unit which is adapted to receive energy from the primary conducting unit, and these modifications are intended to be within the scope of the claims hereto appended. 70

I claim as my invention:

1. In a device of the class described, the combination of an envelope, a support within said envelope, a plurality of standards mounted on said 75

base, a rod secured to one or more of said standards, said rod adapted when heated to selectively radiate energy, a heating conductor positioned adjacent said rod and secured to two or more of said standards through which electrical energy is adapted to be received, a coating of electron emitting material containing alkaline earth metal oxides fixed to said conductor, and an inert gas within said envelope, the pressure of said gas being such as to permit the formation of a layer of ionized gases adjacent said conductor, and said rod and conductor constituting the sole sources of the discharge.

2. An energy radiating device comprising the combination of an envelope, a support mounted in said envelope, a plurality of standards mounted on said support, and a rod connected to one of said standards, a coil of conducting material wound around said rod, a coating containing an alkaline earth metal oxide on said conductor, said conductor being supported by other of said standards, and an atmosphere of inert gases within said envelope, said conductor being connected at its approximate mid-point to the rod and said rod and conductor constituting the sole sources of the discharge.

3. An energy radiating device comprising an envelope, a support within the envelope, a rod mounted on said support adapted when heated to emit luminous energy selectively, an electrical conductor adjacent said rod, a coating of electron emitting material containing alkaline earth metal oxides on said conductor, and an atmosphere of ionizable gas within the envelope at a pressure of about 200 mm. of mercury, said rod and conductor constituting the sole sources of the discharge.

4. An energy radiating device comprising the combination of an envelope, a support mounted in said envelope, a plurality of standards mounted

on said support, and a rod connected to one of said standards, an electric conductor coiled around said rod, said conductor being supported by other of said standards, an atmosphere of inert gas within said envelope, and means including a coating containing an oxide of the alkaline earth metal group on said conductor to ionize the gas in a region confined to the vicinity of said conductor, said rod and conductor constituting the sole sources of the discharge.

5. An energy radiating device comprising the combination of an envelope, a support mounted in said envelope, a plurality of standards mounted on said support, and a rod connected to one of said standards, a coil of conducting material wound around said rod, said conducting material being supported by other of said standards, an atmosphere of inert gas within said envelope including at least ten percent of neon gas, and means to ionize the gas in a region confined to the vicinity of said coil, said means including an electron emitting substance having an electron flow approximately equivalent to barium oxide, said rod and coil constituting the sole sources of the discharge.

6. An energy radiating device comprising the combination of an envelope, a support mounted in said envelope, a plurality of standards mounted on said support, and a rod connected to one of said standards, a coil of conducting material wound around said rod, said conductor being supported by other of said standards, an atmosphere including argon and neon gas within said envelope, and means to ionize the gas in a region confined to the vicinity of said coil, said means including an electron emitting substance containing an oxide of the alkaline earth metal group, said rod and coil constituting the sole sources of the discharge.

CHESTER H. BRASELTON.
